SAFETY LAMP

William M. Garlington, Kansas City, Kans.

Application August 2, 1937, Serial No. 157,019

7 Claims. (Cl. 40—130)

This invention relates to safety lamps and more particularly to portable electric safety lamps for switch cleaners and the like.

In the maintenance of open switches, for instance, during winter weather, traction companies employ switch cleaners whose duty it is to keep the switches from freezing and ice from accumulating upon and between the frogs. These switch cleaners usually protect themselves against traffic hazards at night by employing red lanterns which they place at convenient locations nearby, as a warning of their presence to passing traffic. However, due to the fact that in congested traffic such lanterns are difficult to see and because it is often impossible to find a suitable place in which to deposit the lanterns and, usually, they are placed on the street surface so that the light is but a few inches above the street surface, and may be obscured by snow, such lanterns have been found very inadequate.

The primary object of the invention is to provide a safety lamp which may be readily mounted upon a suitable implement, such as upon the handle of a broom, shovel, switch lever or the like, used by switch and track cleaners, switchmen and others, so that the light therefrom may be easily observed by passing motorists, motormen, truck drivers and others, and the safety factor of the user of the implement will be increased.

It is well recognized that a moving light attracts much more attention than a stationary one, so an important object of the invention is to provide a safety lamp which is adapted to be mounted, preferably upon the upper end of a suitable implement, so that the user of the implement, such as a switch cleaner's broom, as he manipulates the same will cause the light to move about and the light will generally be positioned at a location well above the street surface, where it will be readily observed.

Another object is to provide a safety lamp which is easily but securely mounted upon a suitable implement and takes up but a small space so that it will not interfere with the manipulation of the implement.

Still another object is to provide a safety lamp, in conjunction with an implement, which will permit the user of the implement to employ both of his hands in manipulating the implement.

Other objects and advantages of the invention will be apparent during the course of the following detailed description, taken in connection with the accompanying drawing, forming a part of this specification and in which drawing:

Figure 1 is an elevation of the novel safety lamp mounted upon an implement.

Figure 2 is a vertical section of the novel safety lamp so mounted.

Figure 3 is a top plan of the lamp, parts being broken away to better illustrate portions of the construction.

Figures 4 and 5 are sections substantially upon their respective lines of Figure 2.

Figure 6 is a plan view of an element forming a portion of the novel lamp construction.

Figure 7 is a plan view of another element forming a portion of the novel lamp structure.

In the drawing, wherein for the purpose of illustration is shown a preferred embodiment of the invention and wherein similar reference characters designate corresponding parts throughout the several views, the letter A may designate the novel lamp, including the light ray producing means B, clamping means C therefor, auxiliary switch means D for the light ray producing means B, a transparency E and clamping means F for the transparency. The letter G may designate a suitable handled implement, with which the novel lamp A may be associated.

The light ray producing means B, shown by way of illustration, is a conventional flashlight which may include a substantially cylindrical housing 10 having a length sufficient to accommodate one or more conventional dry cells 11 within its compartment 12. The housing 10 carries a light ray emitter, such as a conventional electric light 13, which may be disposed at one end 14 of the housing 10, so that as the electric circuit is completed by manipulation of the spring retracted switch means 15, which is shown by way of example at the other end or bottom 16 of the housing 10, the light 13 will emit light rays which will be projected outwardly of the housing. The switch means 15 is shown to include a headed member 16^a which is slidably longitudinally of the housing and extends outwardly thereof, terminating in a head 17. Preferably adjacent the end 16, the housing 10 is perforated by a screw threaded perforation 18 for the purpose next described.

As a suitable means C for clamping the means B to a handle, there may be provided a band or strap 20, shown particularly in Figure 7, of suitable springy material. This band is provided, intermediate its ends 21, with a perforation 22 and, adjacent its ends 21, with a pair of perforations 23. Through the perforation 22 may extend the screw threaded shank of a suitable headed member, such as the adjustment screw 25

24, which shank is also adapted to extend through the perforation 18 and cooperate with the screw threads thereof. When this band is bent to the shape shown particularly in Figure 5, it will extend about a portion of the housing 10 and about a portion of the handle of the handled implement F, and the free ends 21 of the band 20 may be drawn towards each other, by means of a suitable bolt 25 extending through the perforations 23, and a cooperating nut 26, whereby the means B may be secured, but detachably secured, to the handle.

15 The auxiliary switch means D may be employed when it would be difficult to keep an electric circuit closed through the means B without manually keeping the switch means 15 closed, as by pressing upon the head 17 with the thumb or finger. Some small flashlights, particularly so-called pencil flashlight, are not equipped with 20 a switch which, when closed, will remain closed until manually released and, in the event such a type of switch is employed, the means D may be incorporated in the novel safety lamp construction. This means D preferably comprises a length 25 30 of suitable material, shown particularly in Figure 6, provided with a screw threaded perforation 31 adjacent one end 32 and a longitudinally extending slot 33 spaced from the perforation 31 and extending towards the opposite end 34. The end 32 may be bent to form a right angle with the remaining portion 35 of the length 30 so that the perforation 31 will substantially align axially with the head 17. Extending through the perforation 31 may be the shank of 35 a suitable set screw 36, with its end in contact with the head 17. The shank of the adjustment screw 24 may extend through the slot 33 with the portion 35 in face-to-face contact with the band 20 where the latter extends over the housing 10. 40 This permits adjustment of the length 30 so that the set screw 36 may just contact the head 17 in one position but when given a turn or partial turn will force the headed member 16a inwardly of the housing 10 and thus close the circuit and 45 the circuit will remain closed until the set screw 36 is again turned to release the spring retracted headed member 16a, as is now apparent. It is also apparent that the head of the adjustment screw 24 will contact the outer face of the portion 35 and will hold it in position but that adjustment of the length of the element 30, longitudinally of the housing 10, may be had by loosening the adjustment screw 24 so that its shank will move longitudinally of the slot.

50 55 The transparency E includes, preferably, a length of suitable material which may be formed into a cylinder 40. This material may be Celluloid and it may be colored red or any suitable color so that the light shining through may appear of the color of the Celluloid. Capping the cylinder 40 may be a closure 41, which may comprise a disc 42, having a downturned rim 43. The disc 42 is preferably provided with a central opening 44 to accommodate the handle of the handled implement G and may also be provided with one or more slots 45 extending from the central opening to allow heat to escape. This closure 41 preferably has at least its inner or lower face 60 suitably treated to provide a reflecting surface and the closure may be secured to the cylinder 40 in any approved way, such as bolt and nut means 46 extending through perforations in the rim 43 and through the cylinder 40. At the 65 opposite end, the cylinder may be secured to a

suitable support which can be said to form a portion of the clamp means F next described.

This means F is quite similar in shape to the conventional electric light globe holder adapted to extend about the open ends of conventional electric light sockets. Preferably included in the means F is a rim portion 50 provided with up-standing lugs 51 containing perforations through which and through suitable perforations in the lower portion of the cylinder 40 extend suitable 10 securing means 52, such as bolts and nuts. This rim portion 50 is supported, in turn, by a band portion 53 connected to the rim portion 50 as by supports 54. The band portion 53 is adapted to extend about the handle of the handled implement G and is preferably of spring metal and provided with a pair of spaced apart arms 55 which extend from the encircling portion 56 of the band and which arms parallel each other. Means for drawing the arms towards each other 15 and tightening the encircling portion 56 about the handle of the handled implement G is provided and may comprise a bolt 57 with the shank thereof extending through aligning perforations in the arms 55, and a cooperating nut 58, as 20 shown particularly in Figure 4. It will be noted, particularly in this figure, that the arms 55 may be drawn into a good holding contact with the outer face of the housing 10 and thus aid in supporting and steadyng the housing 10. 25

The handled implement G is shown as a conventional switch cleaner's broom, having an elongated handle 60, a broom proper 61 at one end and a spud 62 at the other end. However, it is apparent that the implement may take other forms, just so a suitable handle is provided upon which the novel lamp A may be properly secured so that the lighted lamp will attract attention, particularly as the operator moves the implement about while manipulating it in his work. 30

35 After adjusting the means D to function properly as has been explained, the housing may be clamped to the handle 60 as is now apparent and as illustrated particularly in Figures 1, 2 and 5. The transparency E may now be adjusted to 35 cooperate with the means B, by sliding it downwardly over the end 62 of the handle 60 until the end 14, carrying the light 13, will be within the cylinder 40. As will be noted in Figure 2, the cylinder 40 contacts the housing 10 and aids in 40 retaining the latter in place, being reinforced by the rim portion 50 encircling the lower end of the cylinder 40. By tightening the nut 58 upon the bolt 57, the transparency will be held 45 in position and light rays, coming from the light 50 55 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790

The novel lamp A is not intended as a means for affording illumination for the operator, but is a safety lamp adapted, particularly when positioned as described, to notify or warn traffic of the presence of the operator and this warning is especially effective because the light is generally moving about as the operator manipulates the implement of which it forms a part.

Various changes may be made to the form of invention herein shown and described, without departing from the spirit of the invention or the scope of the claims.

What is claimed is:

1. In a signal lamp attachment for implement handles, an annular transparency encircling the handle and providing an annular light chamber about the handle, means for securing the transparency concentrically of the handle, and means for illuminating said chamber.
  2. A signal lamp for attachment to an implement handle, comprising a lamp casing axially receiving the handle therethru and embodying a cylindrical transparency providing an annular light chamber encircling the handle, means adjustably securing the lamp casing to the handle, and means for illuminating said chamber.
  3. In a signal lamp for implement handles, a lamp casing embodying a cylindrical transparency, means securing the transparency concentrically of the handle and providing an annular light chamber about the handle, an electric light bulb for illuminating the chamber, a source of energy for the bulb including a housing, and means for securing the housing to the handle.
  4. A signal lamp for implement handles, comprising a lamp casing including an annular wall of translucent material, a closure cap for one end of the annular wall having an axial handle receiving opening for centering the handle in the annular wall and providing an annular light chamber, and clamping means at the other end of the annular wall for securing the lamp casing to the handle, an electric light bulb for illuminating said chamber, a source of energy for the bulb including a housing, and means for securing the housing to the handle.
  5. A signal lamp for implement handles, comprising a lamp casing including an annular wall of translucent material, a closure cap for one end of the annular wall having an axial handle receiving opening for centering the handle in the annular wall and providing an annular light chamber.
- 10 15 20 25 30 35 40
- chamber, and clamping means at the other end of the annular wall for securing the lamp casing to the handle, an electric flashlight including an elongated housing and a light bulb at one end of the housing, said end of the housing being secured to the handle by said clamping means with the light rays from the bulb projecting into said light chamber, and clamping means for securing the other end of the housing to said handle.
6. In a signal lamp for attachment to an implement handle, an electric flashlight including a housing and a light bulb at the forward end of the housing, clamping means at the rear end of the housing for securing the housing at one end to the handle, a cylindrical transparency encircling the handle and providing an annular light chamber, and clamping means jointly securing the transparency to the handle and the forward end of the flashlight housing to the handle with the light rays from the light bulb directed into said light chamber.
7. In a signal lamp for attachment to an implement handle, an electric flashlight including a housing and a light bulb at the forward end of the housing, clamping means for securing the housing at its rear end to the handle, a lamp casing including a cylindrical transparency encircling the handle and forming an annular light chamber, and means for securing the lamp casing to the handle with the forward end of the flashlight housing received in said light chamber, including a band encircling the handle and a pair of spaced apart clamping arms receiving the forward end of the housing therebetween, and means for contracting the arms for clamping the band about the handle and the arms upon said housing.

What is claimed is:

1. In a signal lamp attachment for implement handles, an annular transparency encircling the handle and providing an annular light chamber about the handle, means for securing the transparency concentrically of the handle, and means for illuminating said chamber.
  2. A signal lamp for attachment to an implement handle, comprising a lamp casing axially receiving the handle therethru and embodying a cylindrical transparency providing an annular light chamber encircling the handle, means adjustably securing the lamp casing to the handle, and means for illuminating said chamber.
  3. In a signal lamp for implement handles, a lamp casing embodying a cylindrical transparency, means securing the transparency concentrically of the handle and providing an annular light chamber about the handle, an electric light bulb for illuminating the chamber, a source of energy for the bulb including a housing, and means for securing the housing to the handle.
  4. A signal lamp for implement handles, comprising a lamp casing including an annular wall of translucent material, a closure cap for one end of the annular wall having an axial handle receiving opening for centering the handle in the annular wall and providing an annular light chamber, and clamping means at the other end of the annular wall for securing the lamp casing to the handle, an electric light bulb for illuminating said chamber, a source of energy for the bulb including a housing, and means for securing the housing to the handle.
  5. A signal lamp for implement handles, comprising a lamp casing including an annular wall of translucent material, a closure cap for one end of the annular wall having an axial handle receiving opening for centering the handle in the annular wall and providing an annular light chamber.
- 10 15 20 25 30 35 40
- chamber, and clamping means at the other end of the annular wall for securing the lamp casing to the handle, an electric flashlight including an elongated housing and a light bulb at one end of the housing, said end of the housing being secured to the handle by said clamping means with the light rays from the bulb projecting into said light chamber, and clamping means for securing the other end of the housing to said handle.
6. In a signal lamp for attachment to an implement handle, an electric flashlight including a housing and a light bulb at the forward end of the housing, clamping means at the rear end of the housing for securing the housing at one end to the handle, a cylindrical transparency encircling the handle and providing an annular light chamber, and clamping means jointly securing the transparency to the handle and the forward end of the flashlight housing to the handle with the light rays from the light bulb directed into said light chamber.
7. In a signal lamp for attachment to an implement handle, an electric flashlight including a housing and a light bulb at the forward end of the housing, clamping means for securing the housing at its rear end to the handle, a lamp casing including a cylindrical transparency encircling the handle and forming an annular light chamber, and means for securing the lamp casing to the handle with the forward end of the flashlight housing received in said light chamber, including a band encircling the handle and a pair of spaced apart clamping arms receiving the forward end of the housing therebetween, and means for contracting the arms for clamping the band about the handle and the arms upon said housing.
